UNITED STATES PATENT OFFICE.

FLOYD DOW, OF PRINCETON, ILLINOIS, ASSIGNOR OF ONE-HALF TO HARRY P. PHELPS, OF PRINCETON, ILLINOIS.

DISPLAY-RACK.

No. 878,872.

Specification of Letters Patent.

Patented Feb. 11, 1908.

Application filed May 9, 1907. Serial No. 372,762.

To all whom it may concern:

Be it known that I, FLOYD Dow, a citizen of the United States, residing at Princeton, in the county of Bureau and State of Illinois, have invented new and useful Improvements 5 in Display-Racks, of which the following is a specification.

My invention relates particularly to display-racks capable of use for storing and 10 displaying wire mattresses; and my primary object is to provide a rack of the character indicated of exceedingly simple construction and admirably adapted to the purpose for which it is intended.

15 The invention is illustrated in its preferred embodiment in the accompanying drawings, in which:

Figure 1 represents an end elevational view of my improved rack with two woven 20 wire mattresses stored therein; Fig. 2, a side elevational view of the rack; Fig. 3, a plan view of the rack, the dotted lines indicating one of the mattresses partially withdrawn from the rack for inspection purposes; Fig. 25 4, a plan section taken as indicated at line 4 of Fig. 1; Fig. 5, a transverse section taken as indicated at line 5 of Fig. 2; and Fig. 6 a broken longitudinal vertical section taken as indicated at line 6 of Fig. 1.

30 In the construction illustrated, the rack comprises two rectangular end-frames A, A¹; a pair of upper longitudinal side-bars A² joining the end-frames; a pair of lower longitudinal side-bars A³ joining the end-frames; 35 a U-shaped cross-member A⁴ connecting the central portions of the upper side-bars A²; a U-shaped cross-member A⁵ connecting the central portions of the lower side-bars A³; longitudinally-disposed upper spacing-bars A⁶ connected with the end-frames and with the U-shaped cross-member A⁴; longitudinally-disposed lower spacing-bars A⁷ connected with the end-frames and with the lower cross-member A⁵; and planks or 40 flooring-members A⁸ supported by the lower cross-members of the end-frames and by the lower intermediate cross-member A⁹. As shown, the spacing-members A⁶, A⁷, are arranged in vertical pairs so as to divide the 45 interior of the display-rack into longitudinal vertical spaces B, which may serve to receive mattresses B¹, B². The rack is open at its ends to permit insertion and withdrawal of the mattresses from either end of the rack. 50 55 The space between the upper bars A⁶ and the

lower bars A⁷, designated B³, is open, so that a table or like article may be stored in the rack when the latter is not occupied by mattresses. In practice, each rack has a half dozen or more of the spaces B, only three 60 of said spaces being shown in the drawing for convenience of illustration. In practice, also, a series of the improved display-racks may be arranged side by side in a row parallel with and some distance from one of the walls 65 of the store-room to enable access to be had to each end of each rack of the series.

The construction of the frame may be varied. As shown, each end-frame comprises an angle-bar suitably notched and 70 bent into rectangular form with the meeting ends brazed together, thereby lending rigidity to the frame. The upper and lower longitudinal side-bars A², A³ may conveniently be angle-bars with the flanges thereof 75 bolted to the inturned flanges of the upright members of the end-frames. The U-shaped intermediate upper cross-member A⁴ is preferably formed by notching an angle bar and bending it into U-shape, the inturned flange 80 of each downturned leg of said U-shaped member being cut away to accommodate the side-bar and the extremity of the other flange being connected by a bolt a with the adjacent side-bar. The lower cross-bar A⁵ 85 comprises preferably a flat bar having its ends turned upwardly and connected by bolts a¹ to the lower side-bars A³. Thus, a flat surface is provided for the support of the intermediate portion of the floor-members 90 A⁸. Each of the members A⁶ preferably comprises an angle-bar having one flange notched and the extremities bent upwardly and secured by bolts a² to the top cross bars 95 of the end-frames. The intermediate portion of each bar A⁶ is joined by a vertical bolt a³ to the web of the intermediate upper cross-member A⁴. Each of said bolts is threaded at both ends and equipped with nuts which serve to clamp the members 100 through which the bolt ends extend. For purpose of adjustment, the web of the cross-member A⁴ is provided with a series of perforations a⁴, and the upper cross-members of the end-frames are provided with perforations a⁵. Thus the bolts a², a³ may be inserted through any desired openings for the purpose of regulating the width of the spaces B. The lower bars A⁷ are formed in the same manner as the bars A⁶ and connected with 110

the lower intermediate cross-member A⁵ and the lower cross-members of the end-frames, the connections being similarly lettered. The end frames are preferably equipped with 5 casters a⁶.

It will be understood that my invention provides a rack of great strength and rigidity, of moderate cost, and it will be observed that the rack may be easily knocked down 10 for purpose of shipment. From Figs. 1 and 3, it will be understood that the mattresses are stored on edge, in pairs, and that mattresses may be withdrawn from either or both ends of a rack for exhibition.

15 The foregoing detailed description has been given for clearness of understanding only, and no undue limitation is to be understood therefrom.

What I regard as new and desire to secure 20 by Letters Patent is:—

1. In a display-rack, the combination of a pair of rectangular end-frames, side-bars connecting said end-frames, upper and lower U-shaped cross-members connecting said 25 side-bars intermediately, and longitudinally-disposed upper and lower spacing-members connected with said end-frames and with the webs of said U-shaped cross-members, for the purpose set forth.

2. The combination of a pair of rectangular end-frames, a pair of upper side-bars connecting said end-frames near their upper ends, a pair of lower side-bars connecting said end-frames near their lower ends, U- 35 shaped cross-members connecting said side-bars, the upper cross-member having its ends turned downwardly and the lower cross-member having its ends turned upwardly, and longitudinally disposed spacing-members 40 within the frame thus formed secured

to said cross-members and to the cross-members of the end frames, for the purpose set forth.

3. The combination of a pair of end-frames, a pair of upper side-bars connecting 45 said end-frames near their upper portions, a pair of lower side-bars connecting said end-frames near their lower portions, U-shaped cross-members connecting said side-bars, the upper U-shaped cross-member having its 50 ends turned downwardly and the lower U-shaped cross-member having its ends turned upwardly, and U-shaped longitudinally-disposed spacing-members having their webs connected with the webs of said U-shaped 55 cross-members and having their extremities joined to the cross-members of the end frames.

4. The combination of a pair of end-frames, connecting-members joining said 60 end-frames, and longitudinally-disposed laterally-adjustable spacing-members connected with the upper and lower cross-members of the end frames and dividing the interior into longitudinal vertical spaces, for 65 the purpose set forth.

5. The combination of a pair of end-frames, side-members connecting said end-frames, U-shaped cross-members connecting said side-members, upper and lower spacing 70 members connected with said cross-members and with the cross-members of said end-frames, and floor-members between the lower spacing-members and supported by the lower U-shaped cross-member and the 75 lower cross-members of the end-frames.

FLOYD DOW.

In presence of—
R. A. SCHAEFER,
A. R. McINTYRE.
